Application July 9, 1938, Serial No. 218,485

13 Claims. (Cl. 62—125)

This invention relates to refrigeration and more particularly to a system for transferring heat so that cooling may be effected at a place above a source of refrigeration.

It is an object of the invention to effect greater efficiency in a system of this character operated by vapor liquid lift action.

Another object of the invention is to provide an improvement in a heat transfer system operated by vapor liquid lift action whereby parts 10 of the system may be conveniently located in practical installations of such systems.

The above and other objects and advantages of the invention are attained by staging the vapor lift action as will appear from the following description and accompanying drawings forming a part of this specification, and of which Fig. 1 more or less diagrammatically illustrates a heat transfer system embodying the invention; and Fig. 2 illustrates a modification of the invention.

In the drawings, the invention is shown in connection with a cooling element 10 of refrigeration apparatus of a uniform pressure absorption type containing a pressure equalizing gas, and like that described in an application Serial No. 107,852 of Albert R. Thomas, filed October 27, 1936. It is to be understood, however, that the particular refrigeration apparatus referred to is merely illustrative and that other types of refrigeration apparatus may be employed.

The cooling element 10 constitutes a source of refrigeration and comprises an outer shell which is embedded in heat insulating material 11. Liquid refrigerant, such as ammonia, enters the upper part of cooling element 10 through a conduit 12. An inert gas, such as hydrogen, enters the upper part of cooling element 10 from the upper end of a cylinder 13 disposed within the shell. Liquid refrigerant evaporates and diffuses into inert gas within cooling element 10 to produce a refrigerating effect. This refrigerating effect is utilized to cool and liquefy a volatile fluid flowing through a coil 14 which is arranged about the cylinder 13 and over the successive turns of which liquid refrigerant descends in sheet-like form.

Since the refrigeration apparatus associated with cooling element 10 forms no part of the invention and is merely illustrative, further description thereof will not be made here. If desired, reference may be had to the aforementioned application for a description of operation of the refrigeration apparatus, the disclosure of which may be considered to be incorporated in this application.

5 The coil 14, which is arranged within and in thermal relation with the cooling element 10, comprises a condensation portion of a heat transfer system forming the subject matter of this invention. The coil 14, which will hereinafter be referred to as a condenser, is located at a lower level than an evaporator 15. The evaporator 15 is of the flooded type and is located in the upper part of a thermally insulated storage space 16 adapted to be cooled to a low temperature. The evaporator 15 includes a receiver 17 having a looped coil 18 connected thereto which is provided with heat transfer fins 19.

15 The condenser 14 and evaporator 15 form part of a closed fluid circuit which is partly filled with a suitable volatile liquid that evaporates within evaporator 15 and takes up heat thereby producing cold. Vapor flows from evaporator 15 into condenser 14 in a manner to be described hereinafter, and the vapor is cooled and condensed by cooling element 10.

20 The heat transfer system forming the invention employs the method of fluid circulation in a heat transfer circuit described in application Serial No. 514,120 of D. B. Knight, filed February 7, 1931, in which volatile liquid is raised by vapor-lift action in a single stage from a place of condensation to a place of evaporation at a higher level. Liquid formed in condenser 14 flows into a 25 downward extending conduit 20 which is connected at its lower end to a nozzle casing 21. Vapor formed in evaporator 15 flows through conduit 22 into nozzle 23, whereby liquid is caused to rise in conduit 24 by vapor-lift action into vessel 25. Vapor and liquid are separated in vessel 25, the vapor flowing through conduits 26 and 27 to condenser 14, and the liquid flowing into a downward extending conduit 28 which is connected at its lower end to a nozzle casing 29.

30 35 40 Vapor formed in evaporator 15 also flows through conduit 30 into nozzle 31, whereby liquid is caused to rise in conduit 32 by vapor-lift action into vessel 33. Liquid in vessel 33 flows into vertical conduit 34 which extends into the lower 45 part of receiver 17, and vapor separated from liquid flows through conduit 27 to condenser 14.

45 50 In the multi-stage liquid lift circuit just described, a series path of flow is provided for liquid while parallel paths of flow are provided for refrigerant vapor or gas. The series path of flow of liquid from condenser 14 to evaporator 15 includes the gas separation vessels 25 and 33, nozzle casings 21 and 29, and connecting conduits 20, 24, 28, 32, and 34. One path of flow of vapor 55 from evaporator 15 to condenser 14 includes con-

duit 22, nozzle 23, conduit 24, gas separation vessel 25 and conduits 26 and 27; and the parallel path of flow includes conduit 30, nozzle 31, conduit 32, gas separation vessel 33 and conduit 27.

During operation of the system, liquid in the upper part of the nozzle casings 21 and 29 is repeatedly segregated in a well-known manner by vapor from the nozzles, whereby slugs of liquid 35 are caused to rise in the riser pipes or conduits 24 and 32 by vapor-lift action.

Liquid is raised in conduits 24 and 32 by bubble action of vapor which flows into these conduits due to a pressure difference in the system resulting from condenser 14 being at a slightly lower pressure than evaporator 15. In the first or low stage lift the weight of the liquid column in conduit 20 balances the weight of the column of liquid slugs 35 and vapor in conduit 24. The liquid slugs pass from the upper end of conduit 24 into vessel 25 as liquid in nozzle casing 21 is repeatedly segregated by vapor from nozzle 23 and liquid slugs are formed in the lower end of conduit 24.

In the second or higher stage lift the weight of the liquid in conduit 28 balances the weight of the liquid slugs 35 and vapor in conduit 32. The liquid slugs 35 pass from the upper end of conduit 32 into vessel 33 as liquid in nozzle casing 29 is repeatedly segregated by vapor from nozzle 31 and liquid slugs are formed in the lower end of conduit 32.

The weight of the column of liquid in conduit 34 overbalances the weight of the column of liquid slugs 35 and vapor in conduits 24 and 32 to cause rise of liquid in these conduits. The weight of this liquid column acts against the gas pressure in conduits 22 and 30 to cause flow of vapor from nozzles 23 and 31 into liquid in nozzle casings 21 and 29 so that this column is referred to as a reaction head.

Thus the weight of the liquid column in conduit 34 gives the motivating force to raise liquid in riser conduits 24 and 32, such raising of liquid being effected by the introduction of vapor into the riser conduits whereby the liquid columns in these conduits are lightened. Reaction heads are also formed by the liquid columns in conduits 20 and 28 to balance the weight of the liquid slugs 35 and vapor in riser conduits 24 and 32 and thereby unobstructively influence the riser columns of liquid and vapor. That is, the liquid columns in conduits 20 and 28 exert weight against the riser columns in conduits 24 and 32 while permitting flow of liquid thereto at all times.

In order to equalize the flow of refrigerant vapor in the different stages, orifices or other suitable flow restriction devices 36 and 37 may be provided in conduits 22 and 30. The restrictions 36 and 37 effect a proper division of vapor flowing from the evaporator 15, so that the rate at which liquid is lifted in the several stages is substantially the same.

By maintaining the rate at which liquid is lifted in the different stages substantially the same, the reaction heads provided by the liquid columns in conduits 20, 28, and 34 are maintained substantially constant. Instead of providing the orifices or flow restriction devices 36 and 37 ahead of the nozzles, they may be located at the discharge side of the gas separation vessels 25 and 33, for instance, in conduits 26 and 27.

Since the weight of the liquid column in conduit 34 must only overbalance the weight of the liquid slugs and vapor in each of conduits 24 and 75

32 to cause rise of liquid in these conduits, the height of the liquid column in conduit 34 is only about half that necessary when lifting liquid in a single stage from condenser 14 to evaporator 15. Since the liquid column above the evaporator 15 is smaller when liquid is raised in several gas stages, a practical advantage is obtained in that the upper part of the heat transfer system can be more conveniently located within the upper part of the storage compartment 16.

While the embodiment of the invention shown in Fig. 1 illustrates a system in which liquid is raised in two stages from condenser 14 to evaporator 15, it should be understood that the invention may be embodied in a system in which liquid is raised in more than two stages. With shorter lifts less vapor is required per pound of liquid raised, so that liquid can be raised in this manner with greater efficiency.

In Fig. 2 is illustrated a modification of the invention which differs from Fig. 1 in that a series path of flow for vapor is provided in the system. In Fig. 2 parts similar to those shown in Fig. 1, such as cooling element 10, condenser 14, and evaporator 15, are designated by the same reference numerals. Vapor formed in evaporator 15 flows therefrom to condenser 14 in a manner to be described hereinafter, and the vapor is cooled and condensed by cooling element 10.

Liquid flows from cooling element 10 through a downward extending conduit 40 which is connected at its lower end to a nozzle casing 41. Vapor formed in evaporator 15 flows through conduit 42 into nozzle 43, as will be described presently, whereby liquid is caused to rise in conduit 44 by vapor-lift action into vessel 45. In vessel 45 vapor and liquid are segregated and liquid is raised in conduit 46 by reformed vapor-lift action into vessel 47. Vapor and liquid are separated in vessel 47, the vapor flowing through conduit 48 to condenser 14, and the liquid flowing into a downward extending conduit 49 which is connected at its lower end to a nozzle casing 50.

Vapor formed in evaporator 15 flows through conduit 51 into nozzle 52, whereby liquid is caused to rise in conduit 53 by vapor lift action into vessel 54. Liquid in vessel 54 flows into evaporator 15 through conduits 55 and 56 forming a U trap 57, and vapor separated from liquid flows through conduit 42 to nozzle 43.

In the multi-stage liquid lift circuit in Fig. 2, a series path of flow is provided for both liquid and vapor. The series path of flow of liquid from condenser 14 to evaporator 15 includes conduit 40, nozzle casing 41, conduit 44, vessel 45, conduit 46, vessel 47, conduit 49, nozzle casing 50, conduit 53, vessel 54, and U trap 57. The path of flow of vapor from evaporator 15 to condenser 14 includes conduit 51, nozzle casing 50, conduit 53, vessel 54, conduit 42, nozzle casing 41, conduit 44, vessel 45, conduit 46, vessel 47, and conduit 48.

During operation of the system, liquid in the upper part of nozzle casings 41 and 50 is repeatedly segregated in a well known manner by vapor from nozzles 43 and 52, respectively, whereby slugs of liquid 58 are caused to rise in conduits 44 and 53. Likewise, liquid in vessel 45 is also repeatedly segregated in the same manner by gas therein, whereby slugs of liquid 58 are caused to rise in conduit 46.

Liquid is raised in conduits 44, 46, and 53 by bubble action of vapor which flows into these conduits due to pressure difference in the system

resulting from condenser 14 being at a slightly lower pressure than evaporator 15. In the first lift the weight of the liquid column in conduit 40 balances the weight of the column of liquid slugs and vapor in riser conduits 44 and 46. Liquid slugs 58 pass from the upper end of conduit 46 as liquid in nozzle casing 41 is repeatedly segregated by vapor from nozzle 43 and liquid slugs are formed in the lower end of conduit 44.

The vessel 45 is provided between riser conduits 44 and 46 to improve the raising of liquid in these conduits. The walls of conduits 44 and 46 are wetted by liquid and some liquid is lost from the rising liquid slugs 58. By providing segregating vessel 45 at the lower end of conduit 46 the attenuation of liquid below this point is prevented. Liquid slugs are reformed in vessel 45 by the vapor therein, whereby the raising of liquid by vapor-lift action is started off again fully at this elevation.

In the second lift a part of the weight of the liquid column formed in conduit 49 balances the weight of liquid slugs and vapor in conduit 53. The liquid slugs 58 pass from the upper end of conduit 53 into vessel 54 as liquid in nozzle casing 50 is repeatedly segregated by vapor from nozzle 52 and liquid slugs are formed in the lower end of conduit 53.

The difference in the height of the liquid columns formed in conduits 55 and 56 is due to the pressure difference in evaporator 15 and vessel 54. The difference in weight of these liquid columns overbalances the weight of the liquid slugs and vapor in conduit 53 to cause rise of liquid in this conduit. The higher column of liquid in conduit 55 reacts to produce the gas pressure in conduit 51 to cause flow of vapor from nozzle 52 into liquid in nozzle casing 50, thereby giving the motivating force to raise liquid in conduit 53.

A part of the weight of the liquid column in conduit 49 balances the weight of the liquid slugs and vapor in conduit 53, as mentioned above. The remainder of the weight of this liquid column overbalances the weight of the column of liquid slugs and vapor in conduits 44 and 46 to cause rise of liquid in these conduits. This may be made clearer by assuming that the pressure in vessel 54 and conduit 42 is at a certain value. At a certain point in the lower end of conduit 49 the pressure is the same as in vessel 54, the weight of the liquid column below such point balancing the weight of the liquid slugs and vapor in conduit 53. From this point in conduit 49 the pressure decreases upwardly through the liquid column, so that the pressure in vessel 47 above the liquid column is less than the pressure in vessel 54. Consequently, there is a pressure difference between conduit 42 and the upper part of conduit 46, whereby liquid is caused to rise due to vapor lift action. The weight of the liquid column in conduit 49 therefore reacts and gives the motivating force to raise liquid in the first stage or lift, such lifting being effected by the introduction of vapor into conduit 44, whereby the liquid column in conduits 44 and 46 is lightened.

The system in Fig. 2 possesses the advantage that liquid does not need to be raised any great distance above the evaporator 15. This is made possible by providing the second lift within storage space 16. The only reaction head required at evaporator 15 is that provided by the difference in height of the liquid columns in 55 and 56 of U trap 57 to cause rise of liquid in conduit 53. In the system in Fig. 2 the evaporator 15

can be positioned very close to the ceiling and in the upper part of storage space 16 and yet all the conduit connections may be kept within the storage space. It is not necessary, therefore, to make provision for extending the conduit connections through the top wall or ceiling of the storage space when the evaporator is located in the extreme upper part thereof.

Although several embodiments of the invention have been shown and described, it will be apparent to those skilled in the art that modifications may be made without departing from the spirit and scope of the invention, as pointed out in the following claims.

15 What is claimed is:

1. In a heat transfer system including a closed fluid circuit partly filled with a volatile liquid and having an evaporation portion at a first elevation and a condensation portion at a lower elevation, structure utilizing vapor produced in said evaporation portion to lift liquid in a plurality of stages between said elevations.

2. In the art of transferring heat with respect to a refrigerating apparatus, the improvement which consists in condensing a heat transfer fluid, producing a first column of liquid condensate and a second column of liquid condensate above the first column, lightening the columns of liquid condensate by the presence of vaporous heat transfer fluid to lift liquid in the first column to the second column and in the latter to a place above the place of condensation, producing vapor, and lifting the liquid in each of said columns by at least a part of the last-mentioned vapor.

3. In refrigerating apparatus including an evaporator containing a volatile liquid and a condensing vessel located below said evaporator and adapted to be cooled by a refrigerating system, a plurality of conduits at different levels and each adapted to hold a liquid column, the one of said conduits at the highest level communicating with said evaporator and having a portion extending below the liquid level therein,

40 means to conduct liquid from said condensing vessel to the top of the lowest liquid column, and means to lift liquid from a lower part of each liquid column, except said highest, to the top part of the next higher liquid column, said lifting means including riser pipes and connections for flow of vapor from the vapor space of said evaporator to said riser pipes, and vapor return lines from the tops of the liquid columns to said condensing vessel, whereby a pressure difference is created and said liquid columns are formed to cause rise of liquid in said riser pipes.

4. In refrigeration apparatus, a part containing refrigerant and a heat transfer system partly filled with a volatile liquid and having a part in heat exchange relation with said refrigerant containing part, said system including a portion in which condensation takes place, a heat receiving portion above condensed liquid in the place of condensation and containing some of said volatile liquid and wherein vapor is produced for producing liquid circulation, and a plurality of vapor-lift conduits connected in series for lifting liquid in a plurality of stages from below the place of condensation to above the condensed liquid, the liquid being lifted in said conduits at least in part by the vapor produced in said heat receiving portion.

5. A method of circulating a volatile fluid which comprises condensing vaporized fluid to liquid at a first level, lifting the condensed liquid

in several stages by vapor-lift action to a level above the first level, segregating the lifting vapor from the raised liquid at the upper part of each stage, evaporating the liquid at said upper level to produce vapor, again condensing the lifting vapor, and producing circulation of the volatile fluid at least in part by the vapor produced at said upper level.

6. A method of circulating a volatile fluid which comprises condensing vaporized fluid to liquid at a first level, lifting the condensed liquid in several stages by vapor-lift action to a level above the first level, separating the lifting vapor from the raised liquid at the upper part of each stage and returning the separated vapor to the place of condensation, evaporating liquid at the upper level to produce vapor, and conducting the last-mentioned vapor in parallel paths of flow to each stage to cause lifting of liquid in the several stages.

7. A method of heat transfer with the aid of a closed fluid system partly filled with a volatile liquid which consists in evaporating liquid at a first elevation, condensing said vapor at a second elevation below said first elevation, lifting the condensate in a plurality of stages to the place of evaporation by vapor-lift action against reaction heads formed by liquid columns of condensate unobstructively influencing the riser columns of liquid and vapor, conducting the vapor produced at said first elevation in parallel paths of flow to the several stages to lift liquid in the latter, separating the lifting vapor from the raised liquid above the reaction heads formed by the liquid columns, returning the separated vapor to the place of condensation, and equalizing the flow of vapor in the several stages to maintain the liquid columns substantially constant.

8. In refrigerating apparatus including an evaporator containing a volatile liquid and a condensing vessel located below said evaporator and adapted to be cooled by a refrigerating system, a plurality of conduits at different levels and each adapted to hold a liquid column, said conduit at the highest level having a lower opening below the liquid level in said evaporator, means to conduit liquid from said condensing vessel to the top of the lowest liquid column, and means to lift liquid from a lower part of each liquid column except the highest, to the top part of the next higher liquid column, said lifting means including riser pipes and connections for parallel flow of vapor from the vapor space of said evaporator to said riser pipes, vapor return lines from the tops of the liquid columns to said condensing vessel, and means to control flow of vapor in said riser pipes.

9. In a heat transfer system including a closed fluid circuit partly filled with a volatile liquid and having an evaporation portion at a first elevation and a condensation portion at a lower elevation, structure to provide a path of flow to said condensation portion for vapor formed in said evaporation portion and to utilize different portions of said path of flow to raise liquid between said elevations in a plurality of stages.

10. In the art of transferring heat with the aid of a closed fluid system partly filled with a volatile liquid and in which vaporized fluid is condensed to liquid at a first level, the improvement which consists in lifting the condensed liquid in several stages by vapor-lift action to a level above the first level, evaporating liquid in the system to produce vapor, lifting liquid in one stage by such vapor, separating the lifting vapor from the raised liquid at the upper part of said one stage and utilizing such separated vapor to lift liquid in another stage, and separating vapor from the raised liquid at the upper part of said other stage and returning the separated vapor to the place of condensation.

11. In the art of transferring heat with the aid of a closed fluid system partly filled with a volatile liquid and in which liquid is evaporated at a first elevation and condensed at a second elevation below said first elevation, the improvement which consists in flowing the condensate upward in a plurality of stages between said elevations by vapor lift action, and supplying vapor in parallel to said several stages under pressure of a liquid column.

12. In a heat transfer system including a closed fluid circuit partly filled with a volatile liquid and having an evaporation portion and a condensation portion below said evaporation portion, structure to conduct liquid upward under vapor lift action in a plurality of stages, structure to hold a column of liquid, and means to conduct vapor under the pressure of said liquid column to said several stages in parallel.

13. In a heat transfer system including a closed fluid circuit partly filled with a volatile liquid and having an evaporator at a first elevation and a condenser at a lower elevation, means including a riser conduit between said elevations for raising liquid therein by lifting action of vapor from said evaporator, and structure connected in said riser conduit for segregating vapor and liquid raised in a portion thereof and effecting reformation of vapor lift action to continue raising of liquid through another portion of said riser conduit.
